(57) CLAIM

The ornamental design for a hair curling kit, as shown and described.

DESCRIPTION

FIG. 1 is a front view of a hair curling kit showing my new design.

FIG. 2 is a back view of the hair curling kit.

FIG. 3 is a first end view of the hair curling kit.

FIG. 4 is a second end view of the hair curling kit.

FIG. 5 is a top view of the hair curling kit; and,

FIG. 6 is a bottom view of the hair curling kit.

The electrical cords are shown broken away to indicate indeterminate length.
